UNITED STATES PATENT OFFICE.

DANA H. BENJAMIN AND HOWARD W. BENJAMIN, OF CLEVELAND HEIGHTS, OHIO,
ASSIGNORS TO THE AMERICAN LAUNDRY MACHINERY COMPANY, OF CINCINNATI,
OHIO, A CORPORATION OF OHIO.

POWER PRESSING MACHINE.

Application filed January 16, 1925. Serial No. 2,859.

To all whom it may concern:

Be it known that we, DANA H. BENJAMIN and HOWARD W. BENJAMIN, citizens of the United States, residing at Cleveland Heights, in the county of Cuyahoga and State of Ohio, have invented certain new and useful Improvements in Power Pressing Machines, of which the following is a specification.

This invention relates to garment pressing machines and more particularly to that class of pressing machines in which the heated head may be actuated by power operated mechanism to reduce the labor of the operator so far as possible.

One object of the invention is to provide an improved pressing machine in which the moving pressing head is mounted to move away from the relatively stationary pressing bed when the press is opened, this motion including a material horizontal separation to produce an unusually wide open effect with complete exposure of the work for the purpose of inspection, arrangement, adjustment thereof or the like, but which press nevertheless produces the actual pressing effect by downward vertical motion of the head toward the bed and without liability of interfering with the lay of the work, and in which all head motion is or may be produced by power actuated mechanism.

A further object of the invention is to provide suitable improved guiding means for controlling the head movement during its actuation by the power mechanism, said guiding means being so arranged that the power mechanism first moves the head substantially horizontally into proper registering relation with the bed and then vertically relative to the bed into pressing engagement therewith.

A further object of the invention is to provide an arrangement of this kind in which the head is carried by a supporting member having swinging motion forwardly and rearwardly in a vertical plane, but in which means is provided for positively preventing sway, oscillation or other movement of said member or of the head in a direction normal to said plane.

A further object of the invention is generally to improve the operating mechanism for producing movement of the head and its supporting member, not only by simplifying said mechanism but also by such an arrange-

ment thereof as will produce the proper motion and pressing effects in the most efficient manner.

A further object of the invention is to provide an improved guard for the entrance to the space between the pressing members, and which guard has motion generally like that of the head, to wit, both horizontal and vertical motions, and is movable both bodily with the head and relatively thereto, said guard having motion across the bed before the head and bed come together so as to brush or wipe away the operator's hand or arm should it chance to be in dangerous position, but without liability of disturbing the lay or arrangement of the garment.

A further object of the invention is to provide a guard of the character described, the motion of which is produced by relative motion between the head and bed.

A further object of the invention is to provide simple and improved controlling mechanism for the press.

Further objects of the invention are in part obvious and in part will appear more in detail hereinafter.

In the drawings, which represent one suitable embodiment of the invention, Fig. 1 is a side elevation, showing the moving parts in three positions, the full lines representing the closed position, the dash double dot lines representing the parts in open position and the dash single dot lines representing the parts in intermediate position; Fig. 2 is a detail sectional elevation of the driving means on the line 2-2, Fig. 4; Fig. 3 is a rear elevation of the press, part being in sectional elevation on the line 3-3, Fig. 1; Fig. 4 is a sectional plan view on the line 4-4, Fig. 3; Fig. 5 is a detail section on a larger scale, through the braking mechanism, the section being taken on the line 5-5, Fig. 2; Fig. 6 is a detail elevation of the timing switch, the view being taken from the left in Fig. 7, with part of the cover broken away to show interior construction; Fig. 7 is a side elevation thereof with a part of the casing broken away to illustrate interior parts; and Fig. 8 is a diagram of the electrical apparatus.

Referring to the drawings the machine illustrated comprises a suitable frame 1 on which is mounted a relatively stationary pressing bed 2 cooperating with a movable

pressing head 3, either or both of said bed and head being hollow and heated by steam or the like in the usual manner, if desired. Below the bed is the work supporting table 1^a. The head 3 is suitably mounted upon a supporting member 4 in the form of a bifurcated arm or lever, its two parallel side portions being connected by cross bars 5, said arm curving rearwardly and downwardly behind the pressing bed and work table 1^a and terminating at its lower end at a low level in the frame beneath the bed 2 and preferably at a point not in front of the same. In the form shown the arm terminates at its lower end in rear of the bed at the back of the press where the two side arms of members 4 are connected by a cross pin or shaft 6 mounted for limited vertical motion in vertically extending elongated slots 7 in the frame (see Fig. 3). Said head supporting member is normally held in an elevated position with the pin 6 at the upper ends of the slots 7 by suitable yielding means, such as a tension spring 8 connected at one end to a sleeve or enlargement 9 of the pin 6 and at its upper end to a rearward extension 10 of the stationary machine frame. Said extension may also serve to steady the member 4 in its swinging movement and limit member 4 to motion only in a vertical plane from front to rear, and preventing any side to side sway, oscillation or other motion of the head supporting member, such effect being accomplished by facing off the side surfaces 11 of the extension 10 where it passes between the side arms of member 4 to form abutments along which the similarly faced surfaces of the arms of member 4 slide.

The head 3 is actuated by suitable power means, shown as an electric motor 12 having its shaft 13 suitably connected, such as by a universal coupling 14, to a shaft 15 provided with a worm 16 driving a worm wheel 17 on a shaft 18 journaled in the side walls of the frame and provided with a crank arm 19 connected by a link 20 to an arm 21 extended forwardly from the head supporting member 4 intermediate its ends. The motor 12 always rotates in the same direction and a full rotation of shaft 18 completes one cycle of operation of the press, moving the head from full open position to full closed position with pressure applied to the work and then returning said head to full open position.

In Fig. 1 the dash double dot lines represent full open position A of the press. Member 4 is yieldingly supported in its uppermost position with the pin 6 at the upper end of the slots 7. The arm 21 extends upwardly and forwardly, while the crank arm 19 and link 20 extend upwardly and rearwardly. When motor 12 is started, as will hereafter appear, its effect is to rotate the

crank 19 in the direction of the arrow X, Fig. 1. The effect of said crank until it reaches the dash single dot position, indicated at B, is to swing the member 4 about the pin 6 as a pivot and carry the head forwardly, largely by horizontal motion, into registering relation with the bed. The last increment of such registering motion is almost a slide across the bed or the work thereon, but without actually touching the work. Analysis of the motion shows that the head approaches the bed so close that it will brush away an operator's hand carelessly allowed to remain upon the bed or the work lying thereon or at least by touching her hand with the hot head will warn her of the closing effect so that the hand is instantly withdrawn, but the head is nevertheless not so close to the work as to disarrange its lay as previously set by the operator. The registering motion terminates with the head directly over the bed in the dash single dot position, Fig. 1. This position is definitely determined in any suitable manner, such as by engagement with a roller 22 on the machine frame of a pad 23 on the front surface of the head support 4 or a cross bar thereof. The pad 23 may be a metal surface or the arm 4 may have a pad of some firm non-yielding noise-reducing material, such as fibre or the like, attached thereto, the use of such material being possible because usually the pressure between the pad and roller during operation of the press is not serious.

The second phase of the operating cycle is the relative vertical motion between the head and bed, produced in this press by bodily motion or motion of translation of the head supporting member 4 and the head carried thereby downwardly. To avoid possible disarrangement of the lay of the work suitable means is provided for guiding the head in its vertical movement, the guiding means in the press shown including both the slots 7 which extend vertically and therefore guide the pin 6 and the lower end of the member 4 during its motion of translation, and the roller 22 and pad 23, which guide the upper portion of the lever 4 and head during the pressing movement. This downward or pressing motion of the head is produced by travel of the crank 19 from the position B to the full line position C, Fig. 1, during which movement the crank 19 and link 20 function as a toggle with an increasingly powerful force exerted upon the head and tending to move it downward into pressing relation with the bed. The parts 19 and 20 during such motion are exerting their effect upon arm 21 by a pull downwardly and slightly toward the front of the press, so that the tendency of said parts is to attempt to move the upper end of lever 4 forwardly. Such motion how-

ever, is prevented by the roller 22 so that the net effect is to hold the pad 23 against roller 22 and to move the lever 4 and head 3 directly downwardly against the bed. 5 When position C is reached the head and bed have been closed together by a pulling effect transmitted directly from the link 20 to the member 4, but not through the pivot on which said member swings. Therefore, 10 by making the lever 4 sufficiently rigid to avoid material spring of the metal the full force of the power mechanism is directly transmitted to the work without material wear or strain upon the pivot 6 or the walls 15 of the slot 7 and lost motion caused by wear is avoided.

In the operation of the press, as will appear, the parts stop in the position C, full closed position, where the work is held under pressure for a sufficient length of time as determined by the operator. The motor is then again started and moves the parts through the third phase of the cycle, to wit, the opening phase, in which the crank arm 25 rotates from position C to its original position A. The first increment of such motion relieves the pressure upon the work. In addition the crank 19 is rotating upwardly and rearwardly, with a tendency to lift the arm 4 and if anything, to push it rearwardly. Pin 6, therefore, immediately rises in the slots 7 by the effect of the spring 8, until, when the pin reaches the upper ends of said slots, the lever 4 begins to swing rearwardly about pin 6 as an axis until the parts reach the initial position A, whereupon the motor is stopped and the parts are ready for another cycle.

To bring the parts to rest accurately in either open or closed full pressure position one of the rotating parts is provided with suitable braking means, preferably controlled in timed relation with the motor operation. As illustrated, one of the motor driven shafts is provided with a brake drum 24, shown as a part of and associated with the coupling 14, said drum cooperating with a brake band 25 normally held in gripping or braking relation with the drum by a preferably adjustable compression spring 26 effective upon a collar 27 at the end of a rod 28 attached to one end of the brake band. The pressure of said spring may be increased to release the brake by energization of an electro-magnet, the coil 29 of which when energized attracts a pivoted armature 30 provided with an arm 31 carrying the adjustable abutment screw 32 located opposite the end of the rod 28.

60 The automatic controlling mechanism for the press includes a suitable timing switch, including a casing 33 and cover 34 surrounding one end of the shaft 18 which actuates the crank 19. The casing is fixedly attached 65 to the machine frame, such as by a bolt 35

passing through an elongated slot in an ear 36 of the casing, enabling the casing and the parts carried thereby to be rotatably adjusted around the axis of the shaft 18 for timing purposes. In the casing are located 70 two conducting segments 37, 38, both cooperating with a rotating brush 39 attached to a conducting ring 40 carried by an insulating block 41 on shaft 18, the block 41 being preferably rotatably adjustable on shaft 75 18 and held by a set screw 42 so that it may be rotated on said shaft for timing purposes. A continuous portion of the conducting ring 40 cooperates with a yielding brush 43 on a stationary insulating block 44 having a 80 binding post 45. Each of the two segments 37, 38 is preferably rotatably adjustable around the shaft 18 in the switch casing, such as by the provision of elongated slots 85 46 in the casing through which pass the bolts 47 for fastening the insulating blocks 47 carrying said segments. Also, each segment terminates in a raised portion 48 over which the rotating brush 39 rides to cause it to jump from segment to segment with a quick 90 make and break.

The electrical circuits are indicated in Fig. 8, in which 49 represents the main line switch, preferably located on the machine frame as shown in Fig. 1, while 50 indicates a normally open starting button located in some position convenient to the operator, such as at the front and at one end of the work table 1^a. Assuming the main switch 49 to be closed, momentary depression of the starting switch 50 completes a circuit through the coil 51 of a starting relay and, let us assume, from brush 39 to segment 37 of the timing switch. Energization of coil 51 closes two sets of normally 100 opening contacts 52, 53. The contacts 53 short circuit the starting button and establish a maintaining circuit for the relay from the line through the wire 54, the core of the relay, contacts 53, winding 51, contact finger 39, segment 37 to the other side of the line, so that momentary depression of the starting button is alone sufficient to energize the relay after which the maintaining circuit maintains said relay energized 105 until otherwise de-energized, as will appear. Closing of contacts 52 completes the motor circuit, from L^a by way of wire 54, contacts 52 and wire 55 through both the armature and field of the motor, as well as through the brake releasing coil 29. Energization of said coil releases the brake and the motor begins to run, moving the shaft 18 and carrying the head from the initial 110 position A to position C, at which time the brush 39 leaves segment 37 and passes upon segment 38. During this jump the maintaining circuit through the relay coil 51 is opened and contacts 52 and 53 immediately 115 open, thereby interrupting the motor cir- 120 125 130

coil and de-energizing coil 29. Spring 30, therefore, immediately applies the brake and halts all parts in the closed full pressure position C. To open the press the starting button is again momentarily depressed, thereby completing the maintaining circuit as before, and again closing a circuit through the motor armature and field as well as through the brake coil 29, but in this case the circuit through the relay 51 passes through the brush 39 and segment 38. As before, the brake is released, and the motor starts, rotating shaft 18 and carrying the parts through the third phase 15 of the cycle from the position C to position A. When this position is reached the rotating brush 39 jumps off from the segment 38 and passes upon segment 37, thereby interrupting the maintaining circuit for the 20 relay coil 51, resulting in opening of contacts 52, 53 and de-energization of the motor circuit and brake coil. The brake is again applied and brings the parts to rest in full open position.

25 While, as stated, the motion of the head horizontally across the bed into registering relation therewith may itself serve to brush away the operator's hands carelessly left in dangerous position, nevertheless an additional guard may in some cases be desirable, and the drawings show such an arrangement. The guard illustrated comprises a 30 guarding member 60 of light form surrounding the front and end edges of the head and carried by arms 61 fixed to a shaft 62 journalled in bosses on the arms of member 4. Shaft 62 is provided with 35 an arm 63 carrying a pin or roller 64 working in a cam slot 65 of a member 66 supported upon the rearward extension 10 of the machine frame, such cam slot at its rear end having a downwardly extending portion 67. Fig. 1 illustrates the closed full pressure position of the press. Remembering that the 40 second phase of the cycle of operations is the downward motion of the head toward the bed it will be clear that during such phase the pin or roller 64 has served as a fulcrum and the downward motion of shaft 50 62 has depressed the guard below the head so that it overlaps the bed and extends across the contacting surfaces between the head and bed. As the press opens the upward motion of member 4 first carries the shaft 62 upwardly and elevates the guard, after which rearward motion of member 4 carries the pin 64 along slot 65 and moves the guard rearwardly across the bed with motion similar to that of the head. Finally as the roller 64 passes into the downwardly extending portions 67 at the rear of the slots 65 the guard is elevated above the head and out of any obstructing position. As the press closes the roller 64 moves forwardly through the cam slot 65 and the

guard moves horizontally forward to an 50 tac work thereon, and in advancing on the head so that the operator's hand or arm is brushed away without the possibility of burning or injury. For example in Fig. 70 the drawings show the forward end of the cam slot 65 as provided with a portion 68 extending upwardly on an inclination toward the front of the machine. The effect of this short portion 68 of the cam slot is 75 to produce some downward motion of the guard during the latter portion of its horizontal motion toward the front of the machine and just before the relative vertical closing motion between the head and bed is 80 produced. In other words, before the relative vertical pressing movement between the head and bed begins, the guard has been moved downwardly to extend below the edge of the bed and thereby insure removal 85 of an operator's hand or arm which might be in dangerous position. Relative vertical movement between the head and bed produces additional downward movement 90 of the guard, as before described.

Obviously by suitable configuration of the cam slot 65 the guard may be given any desired motion relative to the head, and particularly vertical motion relative thereto.

This press is extremely simple and quite 95 safe in operation, but nevertheless is actuated by power and without unnecessary labor by the operator. It widely exposes the pressing bed in open press position so that the work can be readily inspected or arranged. Nevertheless, during the closing and pressure operations there is no liability of injuring the operator and the work is 100 pressed by direct vertical pressure without liability of disturbing the lay. The timing switch parts are capable of adjustment 105 to properly time the points at which the relay coil is deenergized and the brake is applied, so that by simple adjustment the parts can be made to stop in the most efficient positions with maximum pressure and full open position of the pressing members.

Other advantages of the invention will be apparent to those skilled in the art to which it relates.

What we claim is:

1. A garment press, comprising a frame, a stationary work supporting bed, a pressing head, a support therefor extending rearwardly and downwardly behind the bed and at its lower end provided with a horizontal shaft having limited vertical movement in the frame, yielding supporting means for said support, and means for swinging said support about the axis of said shaft to move the head into and out of registration with the bed and for moving said shaft vertically to produce vertical pressing motion of the head toward the bed.

2. A garment press, comprising a frame,

- 1 a stationary work supporting bed, a pressing head, a support therefor extending rearwardly and downwardly behind the bed and at its lower end provided with a horizontal shaft having limited vertical movement in the frame, yielding supporting means for said support, means for swinging said support about the axis of said shaft to move the head into and out of registration with the bed and for moving said shaft vertically to produce vertical pressing motion of the head toward the bed, and means adapted to limit forward swinging motion of said support. 5 and at its lower end mounted in the frame for both swinging and vertical motion, a rotatable crank, a link connecting the same to said support above the lower end thereof, and means for limiting forward motion of said support, whereby said crank produces vertical motion only of said support after said limiting means is reached. 10 2 3. A garment press, comprising a frame, a stationary work supporting bed, a pressing head, a support therefor extending rearwardly and downwardly behind the bed and at its lower end provided with a horizontal shaft having limited vertical movement in the frame, yielding supporting means for said support, means for swinging said support about the axis of said shaft to move the head into and out of registration with the bed and for moving said shaft vertically to produce vertical pressing motion of the head toward the bed, and means adapted to limit forward swinging motion of said support and to guide the same during vertical motion. 15 4. A garment press, comprising a frame, a stationary work supporting bed, a pressing head, a support therefor extending rearwardly and downwardly behind the bed and at its lower end mounted in the frame for both swinging and vertical motion, motor means, and means actuated thereby for producing both of said motions of said support. 20 5. A garment press, comprising a frame, a stationary work supporting bed, a pressing head, a support therefor extending rearwardly and downwardly behind the bed and at its lower end mounted in the frame for both swinging and vertical motion, operating means connected to said support above its lower end and tending to move the same forwardly and downwardly, and means for limiting forward movement of said support, whereby said operating means produces vertical motion only of said support after said limiting means is reached. 25 6. A garment press, comprising a frame, a stationary work supporting bed, a pressing head, a support therefor extending rearwardly and downwardly behind the bed and at its lower end mounted in the frame for both swinging and vertical motion, a rotatable crank, a link connecting the same to said support above the lower end thereof, and means for operating said crank. 30 7. A garment press, comprising a frame, a stationary work supporting bed, a pressing head, a support therefor extending rearwardly and downwardly behind the bed and at its lower end mounted in the frame for both swinging and vertical motion, a guard for said head carried by said support, and connections between said guard and frame arranged to cause the guard to move with the head across the bed during forward and rearward motion of said support and to move downwardly in advance of the head when said support moves downwardly. 35 8. A garment press, comprising a frame, a stationary work supporting bed, a pressing head, a support therefor having swinging motion forwardly and rearwardly and also vertical motion in said frame, a guard for said head carried by said support, and means actuated by relative head and bed motion for operating said guard. 40 9. A garment press, comprising a frame, a stationary work supporting bed, a pressing head, a support therefor having swinging motion forwardly and rearwardly and also vertical motion in said frame, a guard for said head carried by said support, and connections between said guard and frame arranged to cause the guard to move with the head across the bed during forward and rearward motion of said support and to move downwardly in advance of the head when said support moves downwardly. 45 10. A garment press, comprising a frame, a stationary work supporting bed, a pressing head, a support therefor having swinging motion forwardly and rearwardly and also vertical motion in said frame, a guard for said head carried by said support, cam means upon the frame, and means connecting said cam means and guard for actuating the latter. 50 11. A garment press, comprising a frame, a stationary work supporting bed, a pressing head, a support therefor extending rearwardly and downwardly behind the bed and at its lower end mounted in the frame for both swinging and vertical motion, and a single means for producing both of said motions of said support. 55 12. A garment press, comprising a frame, a stationary work supporting bed, a pressing head, a support therefor extending downwardly past the bed and at its lower end provided with a horizontal shaft having limited vertical movement in the frame, yielding supporting means for said support, and means for swinging said support about the axis of said shaft to move the head into and out of registration with the bed and for moving said shaft vertically to produce vertical pressing motion of the head toward the bed. 60 13. In testimony whereof we hereby affix our signatures.
